ROUTE INDICATOR

John E. Gallman, 3927 Sheridan Drive, Charlotte, N.C.

Filed July 12, 1962, Ser. No. 70,904

Term of patent 3½ years

(Cl. D52—1)

FIGURE 1 is a front elevational view of the route indicator showing my new design;

FIGURE 2 is a top plan view thereof;

FIGURE 3 is a rear elevational view thereof;

FIGURE 4 is a bottom plan view thereof looking up at FIGURE 1; and

FIGURE 5 is a side elevational view thereof looking from the left of FIGURE 1.

The dominant features of my design reside in those portions shown in solid lines in the drawings.

I claim:

The ornamental design for a route indicator, substantially as shown and described.
